(57) **CLAIM**

The ornamental design for a lawn and garden tool handle, as shown and described.

DESCRIPTION

FIG. 1 is a perspective view of the present invention;
FIG. 2 is a front view of the present invention, the rear being
a mirror image

FIG. 3 is a side view of the present invention;

FIG. 4 is a top view of the present invention;

FIG. 5 is a bottom view of the present invention;

FIG. 6 is a first environmental perspective view of the
present invention; and,

FIG. 7 is a second environmental perspective view of the
present invention.

The broken line showing of a dibble and a shovel are for
illustrative purposes only and form no part of the claimed
design.
